UNITED STATES PATENT OFFICE.

ARTHUR R. SCHWARZKOPF AND RICHARD R. WAGNER, OF CHICAGO, ILLINOIS, AS-SIGNORS TO THEO. A. KOCHS COMPANY, OF CHICAGO, ILLINOIS, A CORPORATION OF ILLINOIS.

DESIGN FOR A BARBER'S POLE.

Application filed December 8, 1928. Serial No. 29,171. Term of patent 7 years.

To all whom it may concern:

Be it known that we, ARTHUR R. SCHWARZKOPF and RICHARD R. WAGNER, both citizens of the United States, residing at Chicago, in the county of Cook, and State of Illinois, have invented a new, original, and ornamental Design for Barber's Pole, of which the following is a specification, reference being had to the accompanying drawing, forming part hereof.

The figure is a view in elevation of a barber's pole showing our new design.

We claim:

The ornamental design for a barber's pole, as shown.

ARTHUR R. SCHWARZKOPF.
RICHARD R. WAGNER.
